UNITED STATES PATENT OFFICE

125,910

DESIGN FOR A GAME BOARD

John J. Cruise and Elmer G. Anderson,
Hatboro, Pa.

Application December 11, 1940, Serial No. 97,262

Term of patent 7 years

To all whom it may concern:

Be it known that we, John J. Cruise and Elmer G. Anderson, citizens of the United States, residing at Hatboro, in the county of Montgomery and State of Pennsylvania, have invented a new, original, and ornamental Design for a Game Board, of which the following is a specification, reference being had to the accompanying drawing, forming part thereof.

We claim:

The ornamental design for a game board, as shown.

JOHN J. CRUISE.
ELMER G. ANDERSON.
